UNITED STATES PATENT OFFICE.

HENRY DELAWARE HARDCASTLE, OF ATLANTIC CITY, NEW JERSEY.

DRESS-SHIELD STIFFENER.

1,183,874.

Specification of Letters Patent.

Patented May 23, 1916.

Application filed October 8, 1915. Serial No. 54,919.

To all whom it may concern:

Be it known that I, HENRY DELAWARE HARDCASTLE, a citizen of the United States, residing at 121 North Morris avenue, Atlantic City, in the county of Atlantic and State of New Jersey, have invented a certain new and useful Dress-Shield Stiffener, of which the following is a specification.

My invention relates to combined stiffeners and extenders for the flaps of dress shields.

The purpose of my invention is to perform the extending function by elastic flexible means which shall interfere as little as possible with the comfort of the wearer and shall restore the original shape of the flap when the garment is removed from the wearer.

A further purpose of my invention is to provide a resilient and flexible support for the outline of a considerable part of a flap of a dress shield.

A further purpose of my invention is to prevent the curling or rumpling of the flaps of the shield which tend to displace them from their proper positions within the garment.

A further purpose of my invention is to distend the flaps of the shield when not in use, restoring it to its original shape.

A further purpose of my invention is to reduce the number of points of attachment of the shield required to hold it in position.

Further purposes of my invention will appear in the specification and claim thereof.

I have preferred to illustrate my invention by but two of the various forms in which it may appear, selecting forms which are not only practical, efficient and inexpensive, but which at the same time will illustrate the principles of my invention.

Figure 1 is a side elevation of a folded dress shield showing one form of my stiffener in place. Fig. 2 is a section of Fig. 1 taken upon lines 2—2 thereof. Fig. 3 is a side elevation of a stiffener corresponding generally to that shown in Fig. 1, but stiffening an additional area of the shield.

I have applied my invention to the well-known dress shield comprising the outer and inner flaps 5 and 6, joined along a curved line at 7 and each having outer and inner cover members 8, 9, 10, 11 bound about the edges of the flaps, or otherwise united, as by tape 12. Such a shield is or-

dinarily fastened to the garment, not only at the front and back, at 13, 14, but also at one or more other points, such as 15, to keep it spread and prevent curling or crumpling, objectionable both because of the added bulk and because the shield then no longer protects the intended surface. Attachment of the lower part of the shield to the dress causes any strains upon the shield to be transmitted to the dress objectionably.

I have found that the extension (preferably distention) of the lower part of each flap of the shield by a resilient form solves this problem more satisfactorily than the attachment to the garment and avoids the necessity of re-attachment after each removal. I prefer to stretch the flaps by pressure against their lower edges downwardly and, if desired, also laterally by using a resilient insert which conforms substantially to the contour of the lower interior of each flap and which is a little larger across than the space between 15 and the edge 7 or other upper contact. For this purpose I use a flat insert, flexible and resilient within its plane and also for curvature about the arm or body. While I recognize that the insert finds its greatest utility when distending the lower contour of each flap by pressing that contour away from the edge 7, my insert would have some advantage even if its upper edge did not normally engage with the inner surface at 7 or other upper point of engagement, since in either case the insert would prevent excessive crumpling or limit the extent of surface of the flap subject to the crumpling. The insert may be secured to the flap at any point, if desired, as at 17, and the point 17 may be made low enough to hold the insert away from the edge 7, if preferred.

My insert is shown in one form in Fig. 1, as substantially circular in contour, but having a crimped or serpentine perimeter in order to give greater resilience and flexibility. In its most advantageous form, my insert thus presses the entire lower end of the flap away from the upper edge at 7, whatever the position to which the flap is bent about the arm or body.

In the use of my invention with some forms of flap there is a possibility of one or more of the loops or turns of the serpentine perimeter passing over the junction 110

line between the inner faces of the two flaps and resting in the other flap from that in which the main part of the spreader lies. This can readily be prevented by bridging 5 the loops or turns in either of my forms. I have shown it in Fig. 3 as bridging between the points 23 and 24 and as straight in this particular form. It is obvious that both the contour and length of this bridge 10 may be varied to suit the spreader to which it is applied.

I construct the insert of material not subject to rust.

In the form shown in Fig. 3, I have preserved 15 the desirable curved lower edge of the contour and have varied the upper contour to spread a larger surface of the flap,

having the ears 19, 20 for extension into the portions 21, 22 of the flap.

It will be obvious that the exact contour 20 of the insert is of minor importance, providing it maintains the extension of the flap at the required point and possesses sufficient flexibility to accommodate to the parts.

Having thus described my invention, 25 what I claim as new and desire to secure by Letters Patent is:—

A dress shield spreader of curved general contour and having a resilient serpentine perimeter lying in the plane of the approximate circle.

HENRY DELAWARE HARDCASTLE.
